UNITED STATES PATENT OFFICE

2,085,502

COMPACT

Walter Lampl, New York, N. Y.

Application July 1, 1936, Serial No. 88,465

14 Claims. (Cl. 132—83)

This invention relates to an improved compact or vanity case and one object of the invention is to provide a device of this character with an improved powder container so constructed that the powder will be confined therein and prevented from sifting out of the vanity case when the vanity case is not in use and placed in a handbag.

It is another object of the invention to so construct the powder container that when it is mounted in a section of a compact, it will extend for only a portion of the length of the compact section and the remainder of the compact section serve as a well into which the powder is delivered for use. Therefore, powder in desired quantities can be delivered from the container into the well of the compact section for use and the bulk of the powder retained in the container where it will be prevented from spilling out of the compact while the compact is open for use and also prevented from sifting out of a compact placed in a hand bag.

A still further object of the invention is to so form the container that the powder will be well distributed in the well or pan of the compact section when discharged from the container and permitted to be easily taken up by a powder puff.

Another object of the invention is to provide the container with improved means for closing a discharge slot or series of openings formed in a side wall thereof and improved means for actuating the closure to move it from its normally closed position to an opened position.

A further object of the invention is the provision of means for breaking up powder which may become caked in the container and directing loose powder towards the outlet slot or openings, said means being carried by and moved with the actuating means for the closure so that it will be moved whenever the actuating means for the closure is moved.

Still another object of the invention resides in providing a device which is simple and durable in construction, inexpensive to manufacture and one which will be very efficient in operation and application to use.

With these and numerous other objects in view, my invention consists in the novel features of construction, combination and arrangement of parts as will be hereinafter referred to and more particularly pointed out in the specification and claims.

The invention is illustrated in the accompanying drawings, wherein:

Figure 1 is a perspective view of a compact or vanity case having a powder container of the improved construction embodied therein;

Figure 2 is a sectional view taken longitudinally through one section of the vanity case along the line 2—2 of Figure 1;

Figure 3 is a view in top plan showing the closure for the filling opening of the container closed;

Figure 4 is a view similar to Figure 3 showing the closure for the filling opening slid to an opened position;

Figure 5 is a bottom plan view of the container;

Figure 6 is a view similar to Figure 5 showing the closure for the dispensing openings of the container moved to an opened position;

Figure 7 is a view taken along the line 7—7 of Figure 3 and showing the container in side elevation;

Figure 8 is a sectional view through the container taken along the line 8—8 of Figure 3;

Figure 9 is a sectional view taken along the line 9—9 of Figure 3;

Figure 10 is a perspective view of the powder container with mechanism therein removed;

Figure 11 is a perspective view of the actuating mechanism for the closure of the dispensing openings of the container;

Figure 12 is a fragmentary perspective view of a container having a single elongated dispensing opening instead of a plurality of openings; and

Figure 13 is a perspective view of a container having a number of small dispensing openings.

In describing the invention, I shall refer to the drawings in which similar reference characters designate corresponding parts throughout the several views and in which the vanity case or compact illustrated in Figure 1 consists of

companion sections 1 and 2 which are hinged to each other as shown at 3. The section 1 is

equipped with a mirror 4 and the section 2 is formed bordering strip 5 defining a well or pan

6. The section 2 is also provided with a latch 7 of a conventional construction for securing the two sections when closed. While the section 1

has been shown carrying a full length mirror and the section 2 only serves as a powder pan, it is

to be understood that provision may be made for rouge in either the section 1 or the section 2 and that the compact may be constructed to serve as a combined cigarette case and vanity case if so desired by providing the section 1 with cigarette holding means. Such modifications have not

been illustrated as the present invention relates to the powder container mounted in the section 2 and occupying a portion of the length thereof as shown in Figure 1.

5 The powder container 8 which fits into the section 2 is formed of metal or any other desired material and is of such dimensions that it fits snugly into place with its side walls in close contacting engagement with side flanges of the 10 bordering strip 5. Frictional grip between the contacting walls and flanges of the container and the bordering strips may be depended upon to hold the container in place or brazing may be resorted to. The container is of appreciably less 15 length than the section 2 and the exposed side wall 9 of the container is formed near one end with either a series of discharge openings 10 as shown in Figures 10 and 13 or with an elongated opening or slot 11 as shown in Figure 13 through 20 which powder is to pass from within the container into the pan 6 for use. A filling opening 12 through which powder is to be poured into the container is formed in the outer or top wall of the container and along upper and lower side 25 edges of this opening extend flanges or tracks 13 serving to slidably mount a closure plate 14 which has its ends provided with upturned lips or tongues 15 so that the closure plate may be easily slid longitudinally into or out of a closed position. 30 By providing this sliding closure, it may be easily moved to an opened position, powder then poured into the container through the large filling opening, and the closure then slid back into a closed position in which powder will be prevented from 35 spilling out through the filling opening.

In order to prevent the powder from passing out of the container into the pan except when use of the powder is desired there has been provided a closure block 16 which is hollow and open 40 at one end as shown in Figure 8 to receive a spring 17. This spring projects through the open end of the block and is coiled about a pin 18 projecting from a side wall of the container. By this arrangement, the closure block will be normally 45 held in the position shown in Figures 5 and 8 in which it closes the discharge openings 10 as shown in Figures 1 and 7, but may be shifted to an opened position in which it is out of covering relation to the discharge openings as shown in Figure 6. The side face of the block bearing against the wall 9 of the powder container is recessed as shown in Figures 5 and 6 to form a pocket in which packing 19 is mounted so that a tight 50 closure for the discharge openings will be provided and leakage of powder through these openings prevented when the closure is in the closed position. The base 20 of the closure block is also recessed as shown in Figure 8 to receive packing 55 21 which preferably consists of a continuation 60 of the packing 19 as shown in Figure 2, but may be formed separate therefrom and serves as a seal for the slot 22 formed in the top wall of the container. This slot 22 is provided to receive the stem or shank 23 carried by the base and at its 65 outer end provided with a head 24 in order that by placing a thumb or finger upon the head and exerting pressure, the block may be slid from a closed position to an opened position.

It is desired to agitate the powder and feed it 70 towards the discharge openings when the block is slid towards an opened position and in order to do so, there has been provided an agitating and feeding device constructed and mounted as shown in Figures 2, 5 and 6. Referring to these figures, 75 it will be seen that this device consists of a lever

25 having a side extension or arm 26 which is bent intermediate its length so that its free end portion 27 extends longitudinally of the lever. The lever is pivoted to the container by a pin 28 and at its free end is formed with forks 29 5 straddling a tongue or pin 30 carried by the base of the closure block. By this arrangement, the lever will be swung about its pivot pin as the block is shifted longitudinally from the closed position of Figure 5 to the opened position of Figure 6 10 and the toothed head 31 at the free end of the side arm will swing from a position at one side of the block in which it is clear of the base 20 to a position in overlapping relation to the base adjacent one end of the block. During this 15 movement, the toothed head will serve to scrape loose powder in case the powder has formed a cake in the container and the loose powder will be fed towards the discharge openings. It will thus be seen that when the closure block is shifted 20 to an opened position, powder in the container will be directed towards the discharge openings and fed out through these openings into the pan or well 6 where it will flow along the bottom of the pan and become distributed thereon as a thin 25 layer which may be easily taken up by a powder puff for use. A relatively large quantity of powder may be stored in the container, but only a small quantity will flow out through the discharge openings when the block is moved to the 30 opened position and as this powder will be practically all used and the block returned to a closed position by the spring 17, there will be no powder in the pan to sift out between the two sections of the compact when the compact is 35 closed and placed in a hand bag. The fact that all of the powder in the pan is used and the closure block is held in the closed position by the spring 17, prevents powder accumulating in the 40 pan during periods between use of the compact and, therefore, when the compact is opened for use, there will be no danger of powder spilling out of the same and soiling a person's clothing.

From the foregoing description of the construction of my improved device, the operation thereof and the method of applying the same to use will be readily understood. It will be seen that I have provided a simple, inexpensive and efficient means for carrying out the objects of the invention and while I have particularly described the 50 elements best adapted to perform the functions set forth, it is obvious that various changes in form, proportion and in the minor details of construction may be resorted to, without departing from the spirit or sacrificing any of the principles of the invention.

Having thus described the invention, what is claimed is:

1. In a device of the character described, a body formed with a well, a container fitting snugly in said well and being of less length than the well to provide a pan between the container and one end of the well, a side wall of the container being formed with a discharge opening establishing communication between the container and the pan, a closure for the discharge opening mounted in the container for movement into and out of blocking relation to the opening, and means in the container for directing powder towards the discharge opening formed separate from the closure and moved towards the opening for discharging powder through the opening as the closure moves out of blocking relation to the opening.
2. In a compact, a section formed with a well, a powder container in said well spaced from one

end thereof to provide a pan, a side wall of said container having a discharge opening establishing communication between the container and the pan, a closure for said opening slidably mounted in said container, and means for feeding powder in the container towards the opening during movement of the closure to an open position formed separate from the closure and actuated by movement of the closure.

5 10 15 20 25 30 35 40 45 50 55 60 65 70 75

3. In a compact, a body formed with a well, a powder container in said well spaced from one end thereof to provide a powder receiving pan and having an exposed side wall formed with a discharge opening, a closure for the discharge opening slidable in the container against the said side wall longitudinally thereof and yieldably held against movement out of blocking relation to the discharge opening, and means for feeding powder towards the discharge opening pivotally mounted in the container and connected with the closure for movement thereby in a direction to urge powder towards the opening when the closure is shifted towards an opened position.

4. In a compact, a body formed with a well, a powder container in said well spaced from one end thereof to provide a powder receiving pan and having an exposed side wall formed with a discharge opening, a closure for the discharge opening slidable in the container against the said side wall thereof and yieldably held against movement out of blocking relation to the discharge opening, a lever formed separate from the closure and pivotally mounted in said container and connected with the closure for movement thereby when the closure is moved, and a member carried by said lever and adapted to urge powder towards the discharge opening when the lever is swung about its pivot by movement of the closure towards an opened position.

5 10 15 20 25 30 35 40 45 50 55 60 65 70 75

5. In a compact, a body formed with a well, a powder container in said well spaced from one end thereof to provide a powder receiving pan and having an exposed side wall formed with a discharge opening, a closure for the discharge opening slidable in the container against the said side wall and yieldably held against movement out of blocking relation to the opening, a lever in said container pivotally mounted at one end and having a fork at its other end, a pin carried by said closure and engaged in the forked end of said lever to move the lever when the closure is slid, and a side extension for said lever having means carried thereby for urging powder towards the discharge opening when the closure is shifted towards an opened position.

6. In a compact, a body formed with a well, a powder container in said well spaced from one end thereof to provide a powder receiving pan and having an exposed side wall formed with a discharge opening, a closure for the discharge opening slidable in the container against the said side wall and yieldably held against movement out of blocking relation to the opening, a lever in said container pivotally mounted at one end and having a fork at its other end, a pin carried by said closure and engaged in the forked end of said lever to move the lever when the closure is slid, and a side arm projecting laterally from said lever intermediate the length thereof and bent intermediate its length to provide a free end portion extending longitudinally of the lever in transverse spaced relation thereto and terminating in an upstanding toothed head adapted to engage powder and urge the powder towards the dis-

charge opening when the closure is shifted towards an opened position.

7. In a compact, a body formed with a well, a powder container in said well spaced from one end thereof to provide a powder receiving pan and having an exposed side wall formed with a discharge opening, a closure for the discharge opening slidable in the container against the said side wall and consisting of a hollow block open at one end and a backing for the block, a pin projecting from a wall of the container towards the open end of said block, a helical spring extending longitudinally in the block with one end portion projecting from the open end thereof and coiled about said pin, said spring yieldably holding the closure in a normal position for closing the discharge opening, a stem carried by the backing for said block and projecting outwardly through a slot formed in said container, packing carried by the block and its backing and sealing the discharge opening and the slot of the container when the closure is in its closed position, and means for urging powder in the container towards the discharge opening when the closure is shifted towards an opened position.

10 15 20 25 30 35 40 45 50 55 60 65 70 75

8. In a device of the character described including a shell, a container therein formed with an outlet, a closure slidable into and out of closing relation to the outlet, and oscillating means separate from said closure and actuated by the movement of the latter for feeding powder in the container toward said outlet.

9. In a device of the character described, a container formed with an outlet, a closure movable into and out of position to close the outlet, and a feeder for urging powder in the container towards the outlet formed separate from the closure and being pivotally mounted in the container and actuated by the closure.

10 15 20 25 30 35 40 45 50 55 60 65 70 75

10. In a device of the character described, a container having an outlet, a closure for the outlet mounted in the container for reciprocating movement into and out of a closed position, and a powder feeder formed separate from the closure and being mounted for oscillating movement in the container towards and away from the outlet and actuated by movement of said closure.

11. In a device of the character described, a container having an outlet, a closure for the outlet slidable into and out of a closed position in the container, and means for feeding powder to the outlet formed separate from the closure and being pivotally mounted in the container for swinging movement in the plane of the closure towards and away from the outlet and actuated by movement of the closure.

12. In a compact, an open powder dispensing chamber, a powder container in the plane of the dispensing chamber having a side wall facing the chamber, the bottom of the container being flush with the bottom of the chamber, the said side wall of the container being formed with a discharge opening, a closure for the opening mounted within said container and slidably longitudinally of the wall into and out of position to close the opening, and actuating means for said closure extending externally of the container for manual operation.

13. In a compact, an open powder dispensing chamber, a powder container in side by side relation to the dispensing chamber having a side wall facing the chamber and formed with a discharge opening, a closure for the discharge opening movable into and out of position to close the opening, manual actuating means therefor, and means

independent of the closure and actuated thereby for urging powder in the container towards the discharge opening when the closure is operated to uncover the opening.

5 14. In a compact, an open powder dispensing chamber, a powder container having a wall facing the chamber and formed with a discharge opening therein, a closure for said opening slid-

able into and out of effective position, manual actuating means for said closure, and pivoted means independent of the closure and actuated by the latter for urging powder in the container towards the discharge opening when said closure is moved in one direction.

5 WALTER LAMPL.
